UNITED STATES PATENT OFFICE.

CHARLES Z. O'NEILL, OF NEW YORK, N. Y.

STREET-SWEEPER.

SPECIFICATION forming part of Letters Patent No. 663,390, dated December 4, 1900.

Application filed December 6, 1899. Serial No. 739,388. (No model.)

To all whom it may concern:

Be it known that I, CHARLES Z. O'NEILL, a citizen of the United States, and a resident of the city of New York, borough of Manhattan, 5 in the county and State of New York, have invented a new and Improved Street-Sweeper, of which the following is a full, clear, and exact description.

The object of the invention is to provide a 10 new and improved street-sweeper which is simple and durable in construction, very effective in operation, and arranged to thoroughly sweep the dirt from the street-surface into the buckets of an elevator, which in turn 15 delivers the sweepings into a wagon or cart, to the rear end of which the sweeper is removably connected, so that upon moving the vehicle forward the sweeper is dragged along to sweep the street and to deliver the sweepings 20 to the vehicle-body, and when the latter is loaded the sweeper is detached and connected with an empty vehicle to repeat the operation.

The invention consists of novel features 25 and parts and combinations of the same, as will be fully described hereinafter and then pointed out in the claims.

A practical embodiment of my invention is represented in the accompanying drawings, 30 forming a part of this specification, in which similar characters of reference indicate corresponding parts in all the views.

Figure 1 is a sectional side elevation of the improvement on the line 1 1 in Fig. 5. Fig. 35 2 is an enlarged sectional side elevation of the sprocket-wheel and the axle of the sweeper. Fig. 3 is a transverse section of the same. Fig. 4 is an enlarged sectional side elevation of the sweeper-axle and the hub of one of the 40 vehicle-wheels. Fig. 5 is an inverted plan view of the improvement, and Fig. 6 is a plan view of a modified form of sweeping-brush.

The improved street-sweeper is provided with an elevator A, having an inclined frame 45 B, carrying at its side bars boxes C for an axle D to revolve in, said axle carrying at its outer ends side or vehicle wheels E, adapted to travel on the ground. Each of the wheels 50 E is provided at its hub E' (see Fig. 4) with a device F for locking the hub to the axle D when the sweeper is drawn in a forward direction to cause the wheels E to rotate the

axle; but when the sweeper is moved in a backward direction then the said device F permits the wheels to rotate loosely on the 55 axle without rotating the latter. This device F consists of a pin F', adapted to engage a shoulder D' in the axle D, and said pin is fitted to slide in a radial recess in the hub E'. A spring F² presses on the said pin F', and 60 this spring is engaged by a lug F³, held on a spring F⁴, secured to the outside of the hub, the lug F³ and the spring F² extending in the recess containing the pin F'. Thus when the wheel E turns in a forward direction the 65 pin F' by engaging the shoulder D' on the axle draws the latter in the same direction; but when the wheel turns in a backward direction the pin F' slides outward against the tension of the springs F³ F⁴, so that the wheel 70 rotates, but the axle remains stationary.

On the axle D, at or near the middle thereof, are secured collars D², between which extends the head G, mounted to turn loosely on the axle, and connected by a pin G' with a 75 forwardly-extending reach G², engaging at its forward end a pivot H', formed on the end of a screw H, screwing in a keeper H², clipped or otherwise secured to the rear axle I of a vehicle J in the form of a cart or wagon and 80 having a body J', into which discharges the upper end of the elevator A when the sweeper is in use. Thus when the vehicle J is drawn forward a forward movement is given to the elevator mounted on the vehicle-wheels E and 85 connected with the vehicle J by the reach G², as above explained.

In the lower and upper ends of the elevator-frame B are journaled pulleys B' and B², over which passes an endless apron B³, preferably 90 made of canvas or other suitable fabric and having buckets on the outer face of the apron. Each bucket consists of a transverse bar B⁴, preferably made of wood, with rows of bristles B⁵ extending from one face of the bar, 95 near the outer end thereof, to stand parallel with the runs of the apron B³, as will be readily understood by reference to Fig. 1. The sides of the frame B are sufficiently wide to receive the ends of the transverse bars B⁴, which 100 reach from one side to the other, so that any dirt thrown into the buckets by the revolving brush K is held on the apron, the corresponding bar B⁴, and the bristles B⁵, and finally dis-

charged into the vehicle-body J' when the bucket passes over the upper pulley B^2 , it being understood that the upper end of the elevator extends between the extension-boards J^2 of the vehicle-body.

The bearings for the upper pulley B^2 are mounted to slide in slots B^6 , formed in the side bars of the elevator-frame B , and said bearings rest on springs B^7 , contained in said slots. Thus the apron B^8 is normally held taut, and in case one of the buckets when in a lowermost position strikes an obstruction in the street then the apron B^8 is free to pull the pulley B^2 downward against the tension 10 of the springs B^7 until the obstruction has been passed, when the springs B^7 return the pulley B^2 to its former position. Thus it will be seen that when an obstruction is met by one of the buckets there is no danger of the 15 apron being torn or the buckets injured, as the pulley B^2 will yield sufficiently to overcome the obstruction.

On the axle B^8 of the lower pulley B' are held wheels B^9 , adapted to travel on the 20 ground and connected with the axle B^8 by devices F , the same as described in reference to the axle D and the wheels E and shown in detail in Fig. 4.

When the sweeper is drawn forward, the 25 wheels B^9 in traveling on the ground in a forward direction rotate the shaft B^8 to actuate the elevator—that is, to rotate the pulley B' and to cause a traveling motion of the apron B^8 and a rotation of the pulley B^2 . When 30 the sweeper is moved backward, then the wheels B^9 rotate loosely on the shaft B^8 , the same as the wheels E on the axle D .

The revolving brush K has its shaft K' journaled in links L , hung on the axle D , and said 40 links are connected at their rear ends with chains L' , attached to brackets L^2 , secured to the side bars of the elevator-frame. By this arrangement the brush K is flexibly mounted, so as to extend the proper distance at the 45 rear of the lower portion of the elevator and hang at such a height that its bristles will come in proper contact with the surface of the ground to be swept.

In order to rotate the brush K , the shaft K' 50 thereof is provided at one end with a sprocket-wheel N , over which passes a sprocket-chain N' , also passing over a sprocket-wheel N^2 , mounted to turn with the axle D and to oscillate in a transverse direction thereon to 55 permit easy traveling of the chain N' , which is crossed to give a rotary motion to the brush K in the proper direction—that is, in the direction of the arrow a' —to cause the bristles of the brush to sweep the dirt into the buckets 60 of the apron B^8 , traveling in the direction of the arrow b' . The sprocket-wheel N^2 has its hub N^3 mounted on a collar O , secured to the axle D , the hub N^3 being free to oscillate transversely between flanges O' on said collar O .

In order to carry the sprocket-wheel N^2 around with the shaft D and the collar O , the

latter is provided with pivoted shoes O^2 , engaging corresponding recesses in the hub N^3 , (see Figs. 2 and 3,) so that when the shaft D 70 and the collar O turn, then the shoes O^2 carry the sprocket-wheel N^2 along, and at the same time the latter is free to oscillate on the collar and the shoes, as the latter are formed with segmental peripheries and are free to 75 turn on the collar O .

When it is desired to move the wheels B^9 and the brush K off the ground, then the forward end of the elevator-frame B is swung downward toward the reach G^2 , so as to swing 80 the wheels B^9 and the brush K off the ground. In order to hold the forward end of the elevator-frame in proper relative position to the reach G^2 , I prefer to employ a chain P , having a turnbuckle P' for shortening the chain, 85 so as to impart a swinging motion to the elevator-frame for the purpose above described.

In order to prevent the sweepings from passing beyond the sides of the brush K , I form the latter with rows of bristles K^2 , standing 90 radially from the core K^3 , the ends of the rows of bristles being inclined forwardly, as plainly indicated in Fig. 5, so that when the brush is rotated the sweepings at the sides of the brush are thrown inward to prevent any 95 of the dirt from passing beyond the ends of the brush. If desired, a brush K^4 , having rows of bristles spirally arranged, may be employed. (See Fig. 6.)

The operation is as follows: When the several parts are in the position illustrated in Figs. 1 and 5 and the vehicle J is drawn forward, then the brush K is revolved in the direction of the arrow a' , and a traveling motion is given to the apron B^8 in the direction 105 of the arrow b' by the means above explained—that is, the turning of the side wheels E causes a rotation of the brush K , and the traveling of the wheels B^9 on the ground causes a travel of the apron B^8 in the 110 direction indicated. The bristles of the brush K sweep the dirt into the buckets of the elevator and finally discharge between the extension-boards J^2 of the vehicle-body J' into the latter, and when the vehicle J is filled 115 then the sweeper can be readily disconnected from the vehicle, if desired, or the vehicle-body can be emptied of its contents without detaching the sweeper from the vehicle J . In case, however, the reach G^2 is disconnected 120 from the vehicle J by unscrewing the screw H , then the sweeper can be connected with another empty vehicle J , while the loaded vehicle is being drawn to the dump to be emptied of its contents.

In order to prevent the dirt from blowing out of the elevator-buckets, I employ a cover Q , made in one, two, or more sections. A similar cover may be placed over the front part of the vehicle-body J , or I may there employ a flexible cover Q' , wound upon a spring-roller Q^2 and adapted to be stretched across to the other side of the body and to be hooked or otherwise secured thereto.

Having thus fully described my invention, I claim as new and desire to secure by Letters Patent—

1. A street-sweeper comprising a wheeled frame, an elevator having a frame supported to swing on said wheeled frame, a driving ground-wheel for said elevator mounted in the elevator-frame and thereby adapted to be raised from or lowered to the ground by the swinging of the elevator-frame, links pivotally carried by the axle of the wheeled frame, a brush journaled at the rear ends of said links, an adjustable connection from the elevator-frame to the links, and means for driving the brush.

2. A street-sweeper having an elevator, comprising a frame, upper and lower pulleys journaled in the frame, an endless apron passing over said pulleys, buckets on said apron, and formed of transverse bars, and bristles extending from one face of the bar approxi-

mately at right angles to the face, substantially as shown and described.

3. A street-sweeper having an elevator, comprising a frame, upper and lower pulleys 25 journaled in the frame, an endless apron passing over said pulleys, buckets on said apron and formed of transverse bars, bristles extending from one face of the bar approxi- 30 mately at right angles to the face, vehicle-wheels on which said frame is mounted, and driving-wheels for the lower pulley, and arranged to travel on the ground, substantially as shown and described.

In testimony whereof I have signed my 35 name to this specification in the presence of two subscribing witnesses.

CHARLES Z. O'NEILL.
